UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

TYPOGRAPHICAL COMPOSING-MACHINE.

1,116,465.

Specification of Letters Patent.

Patented Nov. 10, 1914.

Application filed May 25, 1914. Serial No. 840,798.

To all whom it may concern:

Be it known that I, CARL MUEHLEISEN, a citizen of the United States of America, residing at 23 Chausseestrasse, Berlin, N. 4, in the Empire of Germany, have invented new and useful Improvements in Typographical Composing-Machines, of which the following is a specification.

This invention relates to improved devices for moving a column of superposed magazines of a typographical composing machine, so as to bring any of them, as required, into operative position relatively to the assembling and distributing mechanisms. It has already been proposed to effect this operation by the use of screws or cam disks but with these devices a long turning movement is always necessary for effecting a change, and this involves a considerable loss of time. The present invention overcomes this difficulty by employing longitudinally adjustable wedges for effecting the changes, these wedges being movable into various positions by the short movement of a lever or other device.

The invention will now be described by reference to the accompanying drawing which shows two examples of the manner of carrying it into effect.

30 In this drawing: Figure 1 is a side elevation of sufficient of a machine to show the application thereto of one of such examples; Fig. 2 is a plan of a part of Fig. 1; Fig. 3 is an end view of part of Fig. 1 as viewed in the direction of the arrow in the last-named figure; and Fig. 4 is a plan showing the second of the two above-named examples.

The magazines, of which there may be any number used (the constructional form illustrated in Fig. 1 has two), are identified by the reference numbers 1 and 2, and are supported as ordinarily upon a magazine frame 3. The magazine frame 3 is supported at four points by means of rollers 4, two near the top and two near the bottom, bearing upon two wedges 5, the wedge surfaces of which are separated by straight surfaces on which the magazines rest when in their respective working positions; in other words, the wedges 5 are formed with steps to support the magazines. The two wedges 5 may be arranged to move simultaneously in opposite directions, in which case they can be pivotally connected to a common adjusting lever 6, which can be

rocked about a fulcrum 7 situated between the points of connection with the wedges. The lever 6 is provided with a handle by means of which it can be rocked on its fulcrum 7 and the wedges be displaced in such a manner that the magazines are evenly raised or lowered. In the just described arrangement the thin ends of the two wedges are directed in respectively opposite directions.

Instead of the foregoing arrangement, the wedges 5 may be arranged to work both simultaneously in the same direction, as shown in Fig. 4, and may, for that purpose, be provided with toothed racks 8 so that they can be geared with and operated by two pinions 9 fast on a shaft 10 which can be manually rotated by means of a crank handle 11. In this arrangement the thin ends of the two wedges 5 are directed both in the same direction. Instead of the wedges 5 being operated by the aforesaid lever 6 or shaft 10, they may be operated by any other convenient means, and instead of the said wedges being arranged to move transversely of the machine as in the foregoing examples, they may be arranged to move in some other direction.

Having described my invention, I declare that what I claim and desire to secure by Letters Patent is:—

1. In a typographical composing machine, the combination with the main frame and a plurality of superposed magazines supported therein, of a plurality of wedges formed with steps and interposed between the main frame and the points of support of the magazines, and means operative to move the wedges longitudinally to bring different steps thereof beneath the said points of support.

2. In a typographical composing machine, the combination with the main frame and a plurality of superposed magazines supported therein, of a plurality of wedges formed with steps and interposed between the main frame and the points of support of the magazines, and means operative to move the wedges longitudinally simultaneously to bring different steps thereof beneath the said points of support.

3. In a typographical composing machine, the combination with the main frame and a plurality of superposed magazines supported therein, of a plurality of wedges

formed with steps and interposed between the main frame and the points of support of the magazines, and means operative to move the wedges longitudinally simultaneously in relatively opposite directions to bring different steps thereof beneath the said points of support.

4. In a typographical composing machine, the combination with the main frame and a plurality of superposed magazines supported therein, of a plurality of wedges formed with steps and interposed between the main frame and the points of support of the magazines, and a hand lever pivotally connected to the wedges and adapted to move them longitudinally simultaneously in relatively opposite directions for bringing different steps thereof beneath the said points of support.

5. In a typographical machine, the combination of a plurality of magazines, and a system of longitudinally movable wedges for shifting the magazines to bring one or another into operative position. 20

6. In a typographical machine, the combination of a plurality of magazines, and a system of longitudinally movable wedges for shifting the magazines to bring one or another into operative position, the said wedges being formed with steps to support 25 the magazines in one or another of their shifted positions.

In witness whereof I have hereunto set my hand in the presence of two witnesses.

CARL MUEHLEISEN.
